LIFTING MECHANISM FOR SKYLIGHTS AND
THE LIKE

Max Anchilowitz, New York, N. Y.

Application April 14, 1939, Serial No. 267,937

8 Claims. (Cl. 268—108)

This invention relates to new and useful improvements in a lifting device for skylights and the like.

More specifically, the invention proposes the construction of a lifting device for skylights and the like characterized by a means operable by a handle for causing a skylight, transom or similarly pivotally mounted window to be opened when the said handle is rotated.

Still further it is proposed to characterize the lifting device by a casing mounted at one side of the frame and a bearing on the other side thereof for rotatively supporting a shaft which extends across the window and which is connected to the window through the medium of links in a manner to cause the window to be opened when the shaft is turned.

Still further it is proposed to provide a handle which extends into said casing at right angles to said shaft and which is provided with a screw portion upon which a follower is mounted in a manner to cause the follower to be moved up and down thereon when the handle is rotated.

Still further it is proposed to provide a means for connecting the follower to said shaft in a manner to cause said shaft to be rotated when said follower moves up and down on said screw portion.

Still further it is proposed to provide a means for locking the handle against being rotated to lock said window in a closed, or various open positions for preventing the window from being opened from the outside.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is an elevational view of a transom having a lifting device constructed according to this invention.

Fig. 2 is a sectional view taken on the line 2—2 of Fig. 1.

Fig. 3 is a sectional view taken on the line 3—3 of Fig. 1.

Fig. 4 is a perspective view of Fig. 1.

Fig. 5 is a view looking in the direction of the line 5—5 of Fig. 1 with the side plate of the casing removed.

Fig. 6 is a view similar to Fig. 5 but illustrating a modification of the invention.

The lifting device for skylights and the like, ac-

cording to this invention, is to be used in conjunction with a frame 10 having a transom 11 or other similar window element pivotally mounted thereon at the sides thereof, as indicated at 12.

The lifting device proper, comprising a casing 13 is mounted on the frame 10 at one side of the transom 11. A bracket 14 is mounted on the frame 10 on the opposite side of the transom 11. A shaft 15 has one of its ends rotatively supported in the bracket 14 and the other of its ends 10 extended into the casing 13. The end of the shaft 15 which is extended into the casing 13 is provided with a collar 16 for preventing the shaft from being accidentally disengaged therefrom. This collar 16 is held in position by means 15 of a set screw 17. The casing 13 has a removable side plate 13^a held in position by means of screws which extend into bosses 13^b formed on a portion of the casing 13.

A screw 18 is rotatively mounted within the 20 casing 13 and is extended at right angles to the shaft 15. A manually operable means is provided for rotating the screw 18. This means comprises a shaft 19 which extends from the bottom of the screw 18 and which has its free end 25 rotatively supported in a bearing 20 mounted upon the wall located beneath the frame 14. The extended end of the shaft 19 is provided with a handle portion 19^a by which it may be conveniently rotated for correspondingly rotating the 30 screw 18.

A follower 21 is mounted upon the screw 18 and is provided with a portion 21^a which extends through a slot 13^c formed in the side of the casing 13. That portion of the follower 21 which extends 35 through the slot 13^c prevents the follower 21 from rotating with the screw 18. Thus the slot 13^c acts to limit the follower 21 against rotating, causing the same to move vertically upwards and downwards depending on the direction in which 40 the screw 18 is rotated.

A radial arm 22 has one of its ends fixedly attached to the shaft 15 immediately adjacent the casing 13. A link 23 has one of its ends pivotally connected to the free end of the radial 45 arm 22. The other end of the link 23 is pivotally attached to the extended portion 21^a of the follower 21 for causing the shaft 15 to be rotated as the follower 21 moves upwards and downwards upon the screw 18.

A second radial arm 24 is mounted upon the shaft 15 intermediate the ends thereof. A link 25 has one of its ends pivotally connected to the free end of the radial arm 24. The other end of the link 25 is pivotally connected to a bracket 50 55

26. This bracket 26 is fixedly attached to the bottom edge portion of the transom 11. Thus as the shaft 15 is rotated through the medium of the radial arm 22 and the link 23, the radial arm 24 will be correspondingly moved to cause the transom 11 to be pivoted about its pivot points 12.

If the handle 19^a is turned in one direction the transom 11 will be pivoted to an open position, 10 and if the handle 19^a is turned in the other direction the transom 11 will be moved back to its closed position.

According to the modification of the invention shown in Fig. 6 a means is provided for locking the shaft 19 against being rotated to hold the transom 11 closed or partially open as desired, and prevent the same from being completely opened from the outside. This means comprises a boss 27 formed on the bottom wall 20 of the casing 13 and through which the shaft 19 extends. The screw 18' is in the form of a tube rotatively mounted between the top and bottom walls of the casing 13. The shaft 19 has a square upper end 19^b which slidably but 25 non-rotatively extends through a square opening formed in the tubular screw 18'. The top end of the shaft 19 extends beyond the top wall of the casing 13 and has a washer 28 freely mounted thereon.

30 A head portion 29 is mounted upon the free end of the shaft 19 and an expansion spring 30 is mounted on the extended end and operates between the adjacent faces of the washer 28 and the head 29 for urging the shaft 19 upwards. A 35 collar 31 is fixedly mounted upon the shaft 19 below the boss 27. The bottom face of the boss 27 is provided with a plurality of serrations 27^a and the adjacent face of the collar 31 is provided with complementary serrations 31^a which 40 are adapted to engage each other for holding the shaft 19 against being rotated. For rotating the shaft it is necessary to pull the handle 19^a downwards against the handle action of the spring 30 to disengage the teeth 31^a from the 45 teeth 27^a. The shaft 19 is then free to be rotated and when the handle 19^a is again released the spring 30 will draw the shaft upwards to re-engage the teeth 31^a with the teeth 27^a. In other respects this form of the invention is 50 similar to the previous form.

55 While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what 60 I claim as new, and desire to secure by United States Letters Patent is:

65 1. A lifting device for skylights and the like, comprising a frame, a transom hingedly mounted in said frame, a casing mounted on one side of said frame, a bearing mounted on the other side of said frame, a shaft extending across said transom and rotatively mounted on said casing and said bearing, a screw rotatively mounted in said casing, manually operable means for rotating said screw, a follower on said screw, 70 radial arms on said shaft, a link pivotally connected with said follower and one of said radial arms, and another link pivotally connected with another one of said radial arms and said transom to move the transom when said screw is turned.

5 2. A lifting device for skylights and the like, comprising a frame, a transom hingedly mounted in said frame, a casing mounted on one side of said frame, a bearing mounted on the other side of said frame, a shaft extending across said transom and rotatively mounted on said casing and said bearing, a screw rotatively mounted in said casing, manually operable means for rotating said screw, a follower on said screw, radial arms on said shaft, a link pivotally connected 10 with said follower and one of said radial arms, and another link pivotally connected with another one of said radial arms and said transom to move the transom when said screw is turned, said follower being formed with a portion extending through a slot formed in the side of said casing for preventing said follower from turning with said screw to limit the movement of said follower to the vertical.

15 3. A lifting device for skylights and the like, comprising a frame, a transom hingedly mounted in said frame, a casing mounted on one side of said frame, a bearing mounted on the other side of said frame, a shaft extending across said transom and rotatively mounted on said casing and said bearing, a screw rotatively mounted in said casing, manually operable means for rotating said screw, a follower on said screw, radial arms on said shaft, a link pivotally connected 20 with said follower and one of said radial arms, and another link pivotally connected with another one of said radial arms and said transom to move the transom when said screw is turned, said casing being formed with a removable side.

25 4. A lifting device for skylights and the like, comprising a frame, a transom hingedly mounted in said frame, a casing mounted on one side of said frame, a bearing mounted on the other side of said frame, a shaft extending across said transom and rotatively mounted on said casing and said bearing, a screw rotatively mounted in said casing, manually operable means for rotating said screw, a follower on said screw, radial arms on said shaft, a link pivotally connected 30 with said follower and one of said radial arms, and another link pivotally connected with another one of said radial arms and said transom to move the transom when said screw is turned, said casing being formed with a removable side.

35 4. A lifting device for skylights and the like, comprising a frame, a transom hingedly mounted in said frame, a casing mounted on one side of said frame, a bearing mounted on the other side of said frame, a shaft extending across said transom and rotatively mounted on said casing and said bearing, a screw rotatively mounted in said casing, manually operable means for rotating said screw, a follower on said screw, radial arms on said shaft, a link pivotally connected 40 with said follower and one of said radial arms, and another link pivotally connected with another one of said radial arms and said transom to move the transom when said screw is turned, the end of said shaft which extends into said casing being provided with a collar fixedly mounted thereon for preventing said shaft from being accidentally disengaged therefrom.

45 5. A lifting device for skylights and the like, comprising a frame, a transom hingedly mounted in said frame, a casing mounted on one side of said frame, a bearing mounted on the other side of said frame, a shaft extending across said transom and rotatively mounted on said casing and said bearing, a screw rotatively mounted in said casing, manually operable means for rotating said screw, a follower on said screw, radial arms on said shaft, a link pivotally connected 50 with said follower and one of said radial arms, and another link pivotally connected with another one of said radial arms and said transom to move the transom when said screw is turned, the end of said shaft which extends into said casing being provided with a collar fixedly mounted thereon for preventing said shaft from being accidentally disengaged therefrom.

55 6. A lifting device for skylights and the like, comprising a frame, a transom hingedly mounted in said frame, a casing mounted on one side of said frame, a bearing mounted on the other side of said frame, a shaft extending across said transom and rotatively mounted on said casing and said bearing, a screw rotatively mounted in said casing, manually operable means for rotating said screw, a follower on said screw, radial arms on said shaft, a link pivotally connected 60 with said follower and one of said radial arms, and another link pivotally connected with another one of said radial arms and said transom to move the transom when said screw is turned, said manually operable means comprising a handle extending from the bottom of said screw in a manner to be rotated for correspondingly rotating said screw.

65 7. A lifting device for skylights and the like, comprising a frame, a transom hingedly mounted in said frame, a casing mounted on one side of said frame, a bearing mounted on the other side of said frame, a shaft extending across said transom and rotatively mounted on said casing and said bearing, a screw rotatively mounted in said casing, manually operable means for rotating said screw, a follower on said screw, radial arms on said shaft, a link pivotally connected 70 with said follower and one of said radial arms, and another link pivotally connected with another one of said radial arms and said transom to move the transom when said screw is turned, said manually operable means comprising a handle extending from the bottom of said screw in a manner to be rotated for correspondingly rotating said screw.

75 8. A lifting device for skylights and the like, comprising a frame, a transom hingedly mounted in said frame, a casing mounted on one side of said frame, a bearing mounted on the other side of said frame, a shaft extending across said transom and rotatively mounted on said casing and said bearing, a screw rotatively mounted in said casing, manually operable means for rotating said screw, a follower on said screw, radial arms on said shaft, a link pivotally connected 80 with said follower and one of said radial arms, and another link pivotally connected with another one of said radial arms and said transom to move the transom when said screw is turned, said manually operable means comprising a handle extending from the bottom of said screw in a manner to be rotated for correspondingly rotating said screw.

transom and rotatively mounted on said casing and said bearing, a screw rotatively mounted in said casing, manually operable means for rotat-
5 ing said screw, a follower on said screw, radial arms on said shaft, a link pivotally connected with said follower and one of said radial arms, and another link pivotally connected with an-
10 other one of said radial arms and said transom to move the transom when said screw is turned, and a means for locking said screw against being rotated.

7. A lifting device for skylights and the like, comprising a frame, a transom hingedly mounted in said frame, a casing mounted on one side 15 of said frame, a bearing mounted on the other side of said frame, a shaft extending across said transom and rotatively mounted on said casing and said bearing, a screw rotatively mounted in said casing, manually operable means for rotat-
20 ing said screw, a follower on said screw, radial arms on said shaft, a link pivotally connected with said follower and one of said radial arms, and another link pivotally connected with an-
25 other one of said radial arms and said transom to move the transom when said screw is turned, said means comprising a boss formed on the bottom face of said casing, said screw being in the form of a tube and having a square open-
30 ing, a shaft forming a handle having a square portion extending through the square opening in said screw, a collar mounted on said handle and engageable against said boss, complementary teeth formed on the adjacent faces of said boss and said collar and engageable with each other

for holding said shaft against being rotated, and resilient means for urging said collar and boss into contact with each other.

8. A lifting device for skylights and the like, comprising a frame, a transom hingedly mounted in said frame, a casing mounted on one side of said frame, a bearing mounted on the other side of said frame, a shaft extending across said transom and rotatively mounted on said casing and said bearing, a screw rotatively mounted in 10 said casing, manually operable means for rotat-
15 ing said screw, a follower on said screw, radial arms on said shaft, a link pivotally connected with said follower and one of said radial arms, and another link pivotally connected with an-
20 other one of said radial arms and said transom to move the transom when said screw is turned, said means comprising a boss formed on the bottom face of said casing, said screw being in the form of a tube and having a square open-
25 ing, a shaft forming a handle having a square portion extending through the square opening in said screw, a collar mounted on said handle and engageable against said boss, complementary teeth formed on the adjacent faces of said boss and said collar and engageable with each other for holding said shaft against being rotated, and resilient means for urging said collar and boss into contact with each other, said resilient means comprising an expansion spring mounted on said 30 shaft for urging the same into a direction in which said collar and said boss will be in engage-
ment.

MAX ANCHILOWITZ.
